UNITED STATES PATENT OFFICE.

ERNEST NORBERT KENNEDY, OF LONDON, ENGLAND.

SAFETY RAZOR.

Application filed November 22, 1926, Serial No. 149,815, and in Great Britain November 24, 1925.

This invention relates to safety razors of the general type wherein a pivotally-supported blade is capable of being stropped without removal to a separate holder. The object of the present invention is to impart to a safety razor of this general type some of the advantages possessed by other well-known types of safety razors the blades of which have two oppositely-disposed cutting edges. A further object is to provide improved means for locking a blade in its operative or cutting position and for releasing it so that pivotal movement may be imparted thereto during stropping.

According to the present invention a safety razor is provided with a head having two blade-carrying portions including guards, blade-holders, and means for locking the blades in position for shaving purposes and for releasing them therefrom for stropping purposes, said blade-carrying portions being arranged back-to-back (i. e. with the cutting edges of the two blades remote from one another or outwardly directed), and said guards and blade-holders being movable, the blade-holder of each portion relatively to the guard and/or the blade-holder of the other portion, in order to permit such automatic and simultaneous reversal of both blades as is necessary for enabling the four sides of the blades to be stropped, alternately in pairs, on a single strop.

For this purpose the two blade-carrying portions may be adapted to be separated from one another to the extent necessary for enabling stropping to be performed, means being provided for locking said blade-carrying portions in mutual juxtaposition for shaving purposes, or alternatively, in mutual separation for stropping purposes.

One blade-carrying portion may be mounted directly on the razor handle and the other on an arm pivoted to said handle, the locking of said portions in mutual juxtaposition or in mutual separation alternatively being effected by means of a sleeve slidable on said handle or said arm.

In the known safety razor a roller is mounted beneath and parallel with the spindle on which the blade is pivotal, said roller and spindle being connected together by a pair of gear wheels outside and at one end of the blade-carrying portion. In the improved safety razor, as the blade-carrying portions are arranged back to back, the gear

wheels are disposed at opposite ends, and the locking of the blades in operative or shaving position may be effected by a lug on one portion engaging a gear wheel (or a part connected therewith), on the other portion when said portions are brought into mutual juxtaposition. For instance, a fixed tooth or fixed teeth on one blade-carrying portion may enter between teeth of a gear wheel on the other portion and thus prevent said wheel from rotating, or an arm on one blade-carrying portion may engage an arm turning as one with one of the gear wheels on the other portion.

For convenience that part of the handle adjacent to the blade-carrying portions may be halved longitudinally, one half being integral with the handle, whilst the other half is pivoted thereto on a transverse axis, said portions being mounted across the free ends of said halves, so that their backs intersect at right angles the plane of division of the handle. On the movable portion of the handle is a sleeve slidable therealong, which sleeve may be provided with lugs adapted to be suitably engaged with the fixed portion of the handle according as the blade-carrying portions are in juxtaposition or separated. This sleeve may be slid along the movable portion of the handle by the thumb of the hand in which said handle is held and, as soon as the lugs have been disengaged, continued movement of the thumb causes pivotal movement of the movable portion of the handle with consequent separation of the blade-carrying portions of the head, and unlocking of the blades. A slight return movement of the thumb enables the sleeve to be re-engaged, and a strop may then be threaded through between the blade-carrying portions and the rollers, and the blades stropped tandem-fashion.

The locking of the movable portion of the handle in its alternative positions could also be effected by mounting on the fixed portion of the handle a leaf spring having a lug adapted to be projected into either of two notches in the movable portion of the handle, the latter carrying a press button adapted for forcing back the leaf spring to disengage its lug from one notch and for releasing said spring, after the movable portion of the handle has been moved, to permit the lug to be projected into the other notch.

If desired the locking of the blades in position for shaving purposes may be effected

as described in the specification of Letters Patent No. 184,808 aforesaid, the pivotal movement of the movable guards being effected by trip lugs or the like on the two portions of the handle.

Instead of the blade-carrying portions being movable towards and away from one another as above set forth, the blade-holders and the parts immediately associated therewith may constitute a structure movable towards and away from the guards constituting another structure, such movement taking place e. g. in a direction normal to the plane in which lie the cutting edges of the blades.

In this form of the invention the strop would be threaded between the blade-holders, and the stropping of the two blades would take place on the opposite sides of the strop, respectively.

In the accompanying drawings, which illustrate one form of the invention, Figure 1 is an elevation looking in a direction parallel to the edges of both blades of the razor; Figure 2 is an elevation viewed at right angles to the plane of Figure 1; and Figure 3 is a plan looking in the direction of the axis of the handle; the razor being shown in Figures 1, 2 and 3 as ready for shaving. Figure 4 is a view similar to Figure 1, but showing the razor in process of being stropped, one of the blades with its carrier and guard being in section. Figure 5 is a face view of a blade; Figure 6 is a similar view showing the blade locking in its holder; and Figure 7 is a corresponding view of the holder without the blade. Figure 8 is a section on line 8—8 of Figure 2; and Figures 9 and 10 are respectively a side and an end elevation of the locking sleeve.

11 is the handle, whereof the forward part of the length is halved longitudinally, the one half 12, which carries the one blade-carrying portion A of the razor-head being integral with the main part 11 whilst the other half 13, which carries the other blade-carrying portion B of the razor-head, constitutes an arm pivoted to the part 12 on a transverse axis 14 normal to the median plane of division.

The two blade-carrying portions A and B of the razor-head are duplicates of one another, and are placed back-to-back. Each comprises a transverse bar or cross-head 15, fixed to the part 12 or 13 of the handle as the case may be, and having formed integrally with it a toothed guard 16 of usual construction; whilst at its ends the cross-head 15 is provided with a pair of upstanding brackets 17, 18 between which the blade-holder 19 is fitted to turn upon trunnions journalled in bearings in the brackets, these trunnions being constituted by the projecting ends of a spindle 20 upon which the holder 19 is fixed. Between the blade-holder spindle 20 and the crosshead 15 is

mounted a cylindrical roller 21 which, like the blade-holder, is fitted to turn upon trunnions journalled in bearings in the brackets 17, 18; the axes of the spindle 20 and roller 21 being parallel to one another, whilst the surface of the roller is parallel to the upper surface of the crosshead 15 at a distance therefrom just sufficient to admit the strop 22 (Figure 4) between them. Outside each bearing 18, the spindle 20 and the trunnion of the roller 21 are geared together by a pair of spur wheels 23, 24, and, outside the spur wheel 24, an extension 25 of the roller trunnion is bent at right angles to form an arm adapted, when the two blade-carrying portions A and B of the razor-head are brought together into shaving position, as in Figure 1, to contact with a stop 26 projecting from the bracket 17 of the other blade-carrying portion so as to lock the roller 21 against rotation in the one direction, rotation in the opposite direction being prevented by contact of the blade-holder 19, through the blade 27, with the back of the guard 16. When the blade-carrying portions A and B are separated from one another, as in Figure 4, each arm 25 is freed from its coacting stop 26 and each roller 21 is thus permitted to turn, during the stopping operation, so as to bring the corresponding blade-holder 19 with its blade 27 from the position shown at the right-hand side to that shown at the left-hand side of Figure 4, and vice versa, at each reversal of movement of the razor as a whole lengthwise of the strop 22. For the purpose of locking the blade-carrying portions A and B in their positions of mutual juxtaposition (Figure 1) or mutual separation (Figure 4), a sleeve 28, shown separately in Figures 8, 9 and 10, is fitted to slide lengthwise of the arm 13 and has a pair of lateral flanges or lugs 29, 29^a which, whilst serving to retain the sleeve upon said arm, are adapted, when the parts 12, 13 of the handle are juxtaposed in shaving position as in Figure 1, to engage the sides of a projection 30 on the fixed part 12 so as to prevent mutual separation of said parts. When, however, the parts 12, 13 of the handle are separated in stropping position as in Figure 4, a portion of the lug 29^a is adapted to engage in a notch 31 at one side of the projection 30, so as to prevent mutual approach of the parts 12, 13. The locking position of the sleeve 28, lengthwise of the movable part 13 of the handle, is in both cases towards the main portion 11 of the handle, and the unlocking position towards the razor-head. In the locking position the sleeve is held by the thumb of that hand which holds the razor during shaving and stropping; after each of which operations the sleeve 28 may be slid by the same thumb upward towards the razor-head so as to un-

lock the parts 12 and 13 from one another, relocking in the new position being effected by a reverse movement of the sleeve under pressure from the thumb.

6. Each blade-holder 19 is of concave-convex cross-section, the blade 27 being held against the concave surface, which is turned towards the guard 16 during shaving, as indicated in Figure 1. Each blade 27 has a single cutting edge 32, but is reversible end-for-end, and is held towards the concave surface of the blade-holder 19 by means of a bar 33 hinged to a stud 34 fitted to turn in a hole in the blade-holder near one end of the latter; the bar 33, which normally extends substantially parallel to the edge of the blade and its holder, being adapted to engage in an undercut notch formed on a lug 35 fixed to the blade-holder near the other end thereof. The blade itself is positioned relatively to the holder 19 by the engagement of the stud 34 and lug 35 with notches 36 formed at the ends of the blade; the action of the bar 33 being to bend the normally flat blade 27 out of its own plane towards the concavity of the holder 19. Such bending may be assisted by forming the blade with a series of slots 37 parallel to its edge 32.

It should be understood that the specific embodiment of the invention here disclosed is merely illustrative and that various changes may be made in the construction and arrangement of parts without departing from the true spirit and scope of the invention.

- Having now particularly described and ascertained the nature of my said invention and in what manner the same is to be performed, I declare that what I claim is:—
40. 1. A safety razor of the kind referred to, comprising a head provided with two blade-carrying portions including guards, blade-holders, and means for locking the blades in position for shaving purposes and for releasing them therefrom for stropping purposes, said blade-carrying portions being arranged back-to-back, and the guards and blade-holders being movable, the blade-holder of each portion relatively to a part of the other portion so as to permit such automatic and simultaneous reversal of both blades as is necessary for enabling the four sides of the blades to be stropped, alternately in pairs, on a single strop.

55. 2. A safety razor of the class described, comprising a head having two blade-carrying portions arranged back-to-back and adapted to be separated to an extent necessary to permit stropping, a guard on each blade-carrying portion, a blade-holder on each blade-carrying portion and movable with respect to the corresponding guard to permit stropping on both sides of a blade held in such blade-holder, means for reversing said blades simultaneously to effect stropp-

ing of said blades alternately in pairs on opposite sides thereof on a single strop, and means for locking said blade-carrying portions in juxtaposition for shaving purposes or in separated condition for stropping.

70. 3. A safety-razor of the class described, comprising a handle, a head including two blade-carrying portions back-to-back and mounted one directly on the razor handle and the other on an arm pivoted to said handle for separation from the other to an extent necessary to permit stropping, a guard on each blade-carrying portion, a blade-holder on each blade-carrying portion and movable with respect to the corresponding guard to permit stropping on both sides of a blade held in such blade-holder, means for reversing said blade-holders simultaneously to enable said blades to be stropped on both sides, and means for locking said blade-carrying portion on said arm in juxtaposition with the blade-carrying portion on said handle.

75. 4. A safety-razor of the class described, comprising a head having two blade-carrying portions arranged back-to-back and adapted to be separated to an extent necessary to permit stropping, a guard on each blade-carrying portion, a blade-holder on each blade-carrying portion and movable with respect to the corresponding guard to permit stropping on both sides of a blade in said holder, means for simultaneously reversing each of said blades including a roller turning due to frictional contact with a strop and connected by gear wheels with the corresponding blade holder, means for locking said blade-carrying portions in juxtaposition, and means including a projection on each blade carrying portion to engage a part connected with one of the gear wheels on the other part for locking each blade in shaving position when the blade-carrying portions are in juxtaposition.

80. 5. A safety-razor of the class described, comprising a head having two blade-carrying portions arranged back-to-back and adapted to be separated to an extent necessary to permit stropping, a guard on each blade-carrying portion, a blade holder on each blade-carrying portion and movable with respect to the corresponding guard to permit stropping on both sides of a blade in said holder, means for simultaneously reversing each of said blades including a roller turning due to frictional contact with a strop and connected by gear wheels with the corresponding blade holder, the gear wheels for the different blade-holders being arranged at opposite ends of the head, means for locking said blade-carrying portions in juxtaposition, and means including a projection on each blade-carrying portion to engage a part connected with one of the gear wheels on the other portion for locking each

- blade in shaving position when the blade-carrying portions are in juxtaposition, said projections being at opposite ends of the head corresponding to the location of the 5 gear-wheels.
6. A safety razor of the class described, comprising a head having two blade-carrying portions arranged back-to-back and adapted to be separated to an extent necessary to permit stropping, a handle having adjacent said head one-half of the handle longitudinally thereof integral with the main part of the handle and carrying one blade-carrying portion and the other half carrying the other blade-carrying portion and being pivoted to the first-mentioned half on a transverse axis normal to the plane of division, the backs of the respective blade carrying portions intersecting said plane at 10 right angles to each other, a guard on each blade-carrying portion, a blade holder on each blade-carrying portion and movable with respect to the corresponding guard to permit stropping on both sides of a blade 15 held in such blade-holder, means for reversing said blade holders simultaneously to enable the blades to be stropped on both sides, and means for locking said pivoted blade-carrying portion in juxtaposition with the 20 blade-carrying portion fixed on the handle.
7. A safety razor of the class described, comprising a head having blade-carrying portions arranged back-to-back, a blade-holder on each of said blade-carrying portions, means for locking blades on said blade-holders in position for shaving purposes and for releasing them for stropping purposes, and means for moving each blade-holder relative to said head in order to effect such 25 automatic and simultaneous reversal of blades as is necessary for enabling the four sides of the cutting edges of the two blades to be stropped, alternately in pairs, on a single strop passing through said head.
8. A safety razor of the class described, comprising a head having two blade-carrying portions arranged back-to-back and adapted to be separated to an extent necessary to permit stropping, a blade-holder on 30 each blade-carrying portion and movable with respect thereto to permit stropping on both sides of a blade held in such blade-holder, means for reversing said blades simultaneously to effect stropping of said 35 blades alternately in pairs on opposite sides thereof on a single strop, and means for locking said blade-carrying portions in juxtaposition for shaving purposes or in separated condition for stropping.
9. A safety-razor of the class described, comprising a handle, a head including two blade-carrying portions back-to-back and mounted one directly on the razor handle and the other on an arm pivoted to said 40 handle for separation from the other to an extent necessary to permit stropping, a blade-holder on each blade-carrying portion and movable with respect thereto to permit stropping on both sides of a blade held in such blade-holder, means for reversing 45 said blade-holders simultaneously to enable said blades to be stropped on both sides, and means for locking said blade-carrying portion on said arm in juxtaposition with the blade-carrying portion on said handle. 70
10. A safety-razor of the class described, comprising a head having two blade-carrying portions arranged back-to-back and adapted to be separated to an extent necessary to permit stropping, a blade-holder on each blade-carrying portion and movable with respect thereto to permit stropping on both sides of a blade in said holder, means for simultaneously reversing each of said 50 blades including a roller turning due to frictional contact with a strop and operatively connected with the corresponding blade-holder to turn the same, means for locking said blade-carrying portions in juxtaposition, and means including a projection on each blade-carrying portion to engage a part connected with the blade-reversing means on the other part for locking each blade in shaving position when the blade-carrying portions are in juxtaposition. 75
11. A safety-razor of the class described, comprising a head having two blade-carrying portions arranged back-to-back and adapted to be separated to an extent necessary to permit stropping, a blade-holder on each blade-carrying portion and movable with respect thereto to permit stropping on both sides of a blade in said holder, means for simultaneously reversing each of said 80 blades including a roller turning due to frictional contact with a strop and operatively connected with the corresponding blade-holder to turn the same, means for locking said blade-carrying portions in juxtaposition, and means including a projection on each blade-carrying portion to engage a part connected with the blade-reversing means on the other part for locking each blade in shaving position when the blade-carrying portions are in juxtaposition. 85
12. A safety-razor of the class described, comprising a head having two blade-carrying portions arranged back-to-back and adapted to be separated to an extent necessary to permit stropping, a blade-holder on each blade-carrying portion and movable with respect thereto to permit stropping on both sides of a blade in said holder, means for simultaneously reversing each of said 90 blades including a roller turning due to frictional contact with a strop and operatively connected with the corresponding blade-holder to turn the same, means for locking said blade-carrying portions in juxtaposition, and means including a projection on each blade-carrying portion to engage a part connected with the blade-reversing means on the other part for locking each blade in shaving position when the blade-carrying portions are in juxtaposition. 95
13. A safety-razor of the class described, comprising a head having two blade-carrying portions arranged back-to-back and adapted to be separated to an extent necessary to permit stropping, a blade-holder on each blade-carrying portion and movable with respect thereto to permit stropping on both sides of a blade in said holder, means for simultaneously reversing each of said 100 blades including a roller turning due to frictional contact with a strop and operatively connected with the corresponding blade-holder, the operative connections for the different blade-holders being arranged at opposite ends of the head, means for locking said 105 blade-carrying portions in juxtaposition, and means including a projection on each blade-carrying portion to engage a part connected with the blade-reversing means on the other portion for locking each blade in shaving 110 position when the blade-carrying portions are in juxtaposition, said projections being at opposite ends of the head corresponding to the location of the operative connections. 115
14. A safety-razor of the class described, comprising a head having two blade-carrying portions arranged back-to-back and adapted to be separated to an extent necessary to permit stropping, a handle having adjacent said head one-half of the handle longitudinally thereof integral with the main part of the handle and carrying one blade-carrying portion and the other half carrying the other blade-carrying portion and being pivoted to the first-mentioned half 120
15. A safety-razor of the class described, comprising a head having two blade-carrying portions arranged back-to-back and adapted to be separated to an extent necessary to permit stropping, a handle having adjacent said head one-half of the handle longitudinally thereof integral with the main part of the handle and carrying one blade-carrying portion and the other half carrying the other blade-carrying portion and being pivoted to the first-mentioned half 125
16. A safety-razor of the class described, comprising a head having two blade-carrying portions arranged back-to-back and adapted to be separated to an extent necessary to permit stropping, a handle having adjacent said head one-half of the handle longitudinally thereof integral with the main part of the handle and carrying one blade-carrying portion and the other half carrying the other blade-carrying portion and being pivoted to the first-mentioned half 130

- on a transverse axis normal to the plane of division, the backs of the respective blade-carrying portions intersecting said plane at right angles to each other, a blade holder 5 on each blade-carrying portion and movable with respect thereto to permit stropping on both sides of a blade held in such blade-holder, means for reversing said blade-holders simultaneously to enable the blades to be 10 stropped on both sides, and means for locking said pivoted blade-carrying portion in juxtaposition with the blade-carrying portion fixed on the handle.
13. A safety razor of the class described, 15 comprising a head having blade-carrying portions arranged back-to-back, a guard and a blade-holder on each of said blade-carrying portions, means for locking blades on said blade-holders in position for shaving purposes and for releasing them for stropping purposes, and means for moving each 20 blade-holder relative to the corresponding
- guard in order to effect such automatic and simultaneous reversal of blades as is necessary for enabling the four sides of the cutting edges of the two blades to be stropped, alternately in pairs, on a single strop passing through said head.
14. A safety razor of the class described, comprising two movable blade-holders each 25 adapted to hold a blade, blade-guards one for each of said blade-holders, means for locking the blades in position for shaving purposes and for releasing them for stropping purposes, means for permitting relative movement of said blade-holders and guards to enable reversal of said blades, and means for automatically and simultaneously reversing both of said blades to enable the 30 four sides of the blades to be stropped alternately in pairs on a single strop.

In testimony whereof I affix my signature.

ERNEST NORBERT KENNEDY.
